LEATHERED LET-OUT FUR FOX TAIL

Morris Schatz, Brooklyn, N. Y.

Application November 14, 1939, Serial No. 304,385

2 Claims. (Cl. 149—28)

This invention relates to leathered let-out fur fox tail and methods of producing the same.

An object of this invention is to provide a fur-piece made from a fur tail or other piece of fur, 5 and having a length greater than the normal length of the piece of fur from which it is made.

It is well known that fur tails do not have very much value. With the present invention the fur tail can be converted to a length approximately 10 twice its original length, so that it may be used for making fur jackets known as "chubbies."

In carrying out the invention, the animal skin bearing the fur is cut at spaced points, and pieces of leather, or other suitable material, are 15 stitched to or between the cut portions, to lengthen the piece of fur. The interposed pieces of leather, or other suitable material, are preferably sufficiently narrow so that the fur hairs of adjacent pieces of fur will contact, so that 20 there are no breaks visible in the fur.

Still another object of this invention is to provide a strong and durable fur piece, and a highly economical, practical and efficient method of producing the same.

Other objects of this invention will in part be 25 obvious and in part hereinafter pointed out.

The invention accordingly consists in the combination of steps, features of construction, combinations of elements, and arrangement of parts 30 which will be exemplified in the method and construction hereinafter described, and of which the scope of application will be indicated in the following claims.

In the accompanying drawing, in which is 35 shown one of the various possible illustrative embodiments of this invention,

Fig. 1 is a top plan view of the leather side of a piece of fur made from a tail, and showing the lines along which the piece of fur is cut, in 40 dot, dash lines;

Fig. 2 is a top plan view of one of the pieces cut from the fur tail, shown in Fig. 1;

Fig. 3 is a top plan view of one of the leather 45 inserts;

Fig. 4 is a top plan view of the leathered let-out fur tail, made in accordance with the invention; and

Fig. 5 is an enlarged, cross-sectional view taken on line 5—5 of Fig. 4.

It is well known that the tail of a fur bearing animal has limited uses in making fur garments and its value therefore is small. Such fur tails 50 cannot be used in making fur jackets known as "chubbies," and made of pieces of fur running up and down. Such jackets are usually made

from pieces of fur from the bodies of animal skins. It is therefore an object of the present invention to provide a method for converting a tail into a piece of fur which may be used in making a fur garment.

In accordance with the invention, a tail of a fur bearing animal, such as a fox, is slit longitudinally and then flattened out and trimmed so that it has the shape of a piece of fur 10, shown 10 in Fig. 1 of the drawing. This piece of fur has inclined longitudinal edges 11, increasing in width from one end to the other, and substantially V-shaped end portions 12 and 13.

The leather portion of the piece of fur 10 is then cut along parallel lines 15, inclined to the 15 edges 11, to form substantially parallelogram shaped pieces 20. There is then stitched between the pieces 20, substantially parallelogram shaped pieces 21 of artificial leather, or any other suitable material.

The shape and dimensions of each piece 21 is preferably substantially the mean between the dimensions of the pieces 20 on opposite sides thereof. The pieces 21 are stitched to the pieces 20, along lines of stitching 22. The width of the 25 pieces 21 are preferably substantially similar to the width of the pieces 20. The width of each piece 21 is preferably less than one-half inch. Said pieces may be between one-quarter and three-eights of an inch to give good results. 30 The pieces 21 must be sufficiently narrow, so that the fur 25 on the pieces 20 on opposite sides thereof, are in contact, so as to hide any break in the fur.

The composite member 30, shown in Fig. 4, 35 after the pieces 20 and 21 are stitched together, may be used in making waist length jackets known as "chubbies," or other garments. When the pieces 20 and 21 are of equal width, the length of member 30 is substantially twice the 40 length of the original furpiece 10. The value of the fur tail is greatly enhanced by making it longer, so as to increase the use thereof.

With the improved method of making the leathered let-out furpiece 30, the coloring of the fur is not materially altered because the pieces 20 cut from the tail 10 have the same relation to one another in the piece 30, as they had in the tail 10.

It will thus be seen that there is provided an 50 article and method in which the several objects of this invention are achieved, and which is well adapted to meet the conditions of practical use.

As various possible embodiments might be 55 made of the above invention, and as various

changes might be made in the embodiment above set forth, it is to be understood that all matter herein set forth or shown in the accompanying drawing is to be interpreted as illustrative and 5 not in a limiting sense.

Having thus described my invention, I claim as new and desire to secure by Letters Patent:

1. In the art of fur manufacture, the method which consists in longitudinally slitting the tail 10 of a fur-bearing animal, then flattening out the slit tail, then cutting the skin of the slit tail along adjacent parallel lines inclined to the longitudinal axis of the tail to form narrow pieces of slit fur, then stitching narrow pieces of 15 flexible sheet material between the narrow pieces of fur while maintaining said pieces in their original sequence in the tail, thereby materially increasing the length of the tail without materi-

ally altering the natural colored pattern of the fur of the tail.

2. A fur piece comprising narrow pieces of fur from the tail of a fur-bearing animal, the skin of said pieces of fur each being in the shape of a parallelogram of progressively increasing length but of substantially the same width, pieces of flexible sheet material, of the same width as said skins of the fur pieces, between adjacent fur pieces and stitched thereto, said pieces of fur being in their natural sequence, said pieces of flexible material being of a shape complementary with the skins of said pieces of fur and alternately arranged therebetween, whereby the original length of the tail is approximately doubled 10 and the natural colored pattern of the fur of the tail is not materially altered. 15

MORRIS SCHATZ.
